UNITED STATES PATENT OFFICE.

WILLIAM RODGERS, OF HAMILTON, ONTARIO, CANADA.

ELECTRIC GENERATOR OR MOTOR.

1,093,650.

Specification of Letters Patent. Patented Apr. 21, 1914.

Application filed September 13, 1913. Serial No. 789,682.

To all whom it may concern:

Be it known that I, WILLIAM RODGERS, a subject of the King of Great Britain, and residing at Hamilton, in the county of Wentworth and Province of Ontario, Canada, have invented new and useful Improvements 5 in Electric Generators or Motors, of which the following is a specification.

My invention relates to improvements in 10 electric generators or motors and specially consists of a number of bent dovetail plates, preferably of steel, rigidly secured in divisioned transverse order to the inner part of the circular cast iron stationary frame.

15 The objects of my invention are, first, to provide independent dovetail plates made of wrought iron or steel secured to the frame, thereby eliminating the machining out of dovetail slots in the blank casting, or frame; second; in the introduction and use of my 20 dovetail-plate more space for ventilation and clearance for bolts is obtained when using certain end plates on split frames of electrical machines; third, by the use of my 25 dovetail-plates, they may be made in different standard lengths and placed in stock ready for assembling; fourth; to provide a frame bored out to a given dimension with screw holes drilled therein ready prepared 30 to receive my dovetail-plates, of required dimension, thereby considerably reducing the time and cost of building the frame.

Further, in this invention, the dovetail-plates can be made far in advance of the 35 frame casting, for assembling and other purposes.

Further, this invention provides against delay in constructing and machining out dovetails in the solid frame, especially so 40 should blow holes be encountered in the frame casting, this would necessitate another casting, the advantages of my invention will therefore be readily perceived.

I obtain these objects by the mechanism 45 illustrated in the accompanying drawing, in which:—

Figure 1 is an elevation of an electric machine, generator or motor partially in section, showing my method of construction 50 and design of five of my dovetail-plates secured in position to the machine and rigid therewith, together with a segment portion of the iron laminated punchings in four of said dovetails. Fig. 2 is an end elevation of 55 the same, partly in section, showing position of the dovetail-plates secured to the frame

of the machine. Fig. 3 is a plan of a dovetail-plate showing the counter-sunk holes, for machine screws, therein. Fig. 4 is an enlarged cross sectional elevation of my 60 dovetail-plate, and the frame, showing said plate secured to the frame of the machine by means of a counter-sunk head machine screw.

Similar characters of reference refer to 65 similar parts throughout the several views.

In the drawing 2, is the cast iron stationary frame of an electric generator, or motor, and has a plurality of equally spaced seatings around the inner circumference or bore part 70 of the frame; thereby forming equally spaced air recesses 4, between said seatings.

5, are the dovetail-plates bent out of wrought iron or steel and the base parts of said plates are secured on the seatings 3 of 75 the bore. The dovetail plates 5, have counter-sunk holes 6, through the base portions thereof, as seen in Figs. 3 and 4 of the drawing, and said plates are rigidly secured to the bore seatings by means of the machine 80 screws 8, which screw into the threaded holes 9 in the frame, two machine screws secure each dovetail-plate to each seating of the frame.

It will be noticed that the base and the 85 beveled sides of the dovetail-plates are of the same thickness of material throughout, therefore the same may be easily bent by machinery from one flat piece of suitable metal, preferably steel plate, to the desired form of 90 dovetail, the outer side following in parallel order the form of the innerside. The countersunk heads of the screws are shown flush with the inner base parts of the dovetail openings of the plates so as not to interfere 95 with the punchings 10, in said dovetails, said punchings 10, are not new, they being common to this class of electric machines.

The construction shown in Fig. 4, is of light weight and durable, and the dovetail 100 plates can easily be removed and replaced by others.

What I claim as my invention and desire to secure by Letters Patent, is:—

1. In an electric generator, or motor, a 105 frame having an inner bore, dovetail-plates equally spaced apart on said bore and having counter - sunk holes therethrough threaded holes in the frame opposite to the holes in the plates, and screws provided with 110 heads to fit the holes in the plates to rigidly secure said plates to the frame, and to be

flush with the inner base of the dovetail-plates.

2. In an electric generator or motor, a frame having an inner bore, dovetail plates
5 spaced apart on said bore and having countersunk holes through the base parts thereof, threaded holes in the frame opposite to the holes in the plates, and means in said holes to rigidly secure the plates to the frame, and
10 to be flush with the inner base of the dovetail-plates.

3. In an electric generator or motor, a stationary frame having an inner bore with

equally spaced recesses around the same, dovetail-plates, having counter-sunk holes 15 through the base parts thereof, on said bore, threaded holes in the frame opposite to the holes in the plates, and means in said holes to rigidly secure the plates to the frame and to be flush with the base of the inner sides of 20 the dovetail.

WILLIAM RODGERS.
